K. KLETTE,
GUN WITH ADJUSTABLE CRANKED AXLE TREE,
APPLICATION FILED FEB. 10, 1914.

Patented Aug. 8, 1916.

UNITED STATES PATENT OFFICE

KURT KLETTE, OF DUSSELDORF, GERMANY, ASSIGNOR TO RHEINISCHE METALL-WAAREN- UND MASCHINENFABRIK, OF DUSSELDORF-DERENDF, GERMANY, A CORPORATION OF GERMANY.

GUN WITH ADJUSTABLE CRANKED AXLETREE.

1,194,031.

Specification of Letters Patent.

Patented Aug. 8, 1916.

Application filed February 10, 1914. Serial No. 817,843.

To all whom it may concern:

Be it known that I, KURT KLETTE, engineer, a subject of the German Emperor, residing at 46 Marschallstrasse, Dusseldorf, 5 Germany, have invented certain new and useful Improvements in Guns with Adjustable Cranked Axle-trees; and I do hereby declare the following to be a full, clear, and exact description of the invention, such as 10 will enable others skilled in the art to which it appertains to make and use the same.

The present invention relates to guns having adjustable cranked axle-trees for setting the gun to an elevated or depressed firing 15 position.

According to the present invention the masses are so distributed with respect to the wheel axis that in the traveling position of the gun, that is when it is limbered 20 up, these masses counterbalance each other about the wheel axis so that the pressure exerted by the trail on the limber is entirely or nearly removed.

In the accompanying drawings, Figure 1 25 shows the gun in depressed position, and Fig. 2 in elevated position. Fig. 3 is an enlarged sectional view through the hub of one of the wheels. Fig. 4 is a fragmentary view of the locking bolt.

30 In the normal traveling position, shown in Fig. 1, the trunnions of the gun are in line with the hollow axles *a* of an axle-tree crank *b*, the axles *a* being releasably held in this position by locking means which comprises 35 a plug *c* fitting in the outer end of the axle and having a handle *d* for moving the plug with its bolt *g* against the pressure of a spring *h* which latter encircles a reduced portion of the bolt and has one end bearing 40 against an abutment *i* in the axle *a*. The plug is slotted as at *e* to permit its longitudinal movement without necessitating removal of the linch pin *f* by which the wheel is held to the axle. When the gun is to be moved

from the depressed position, shown in Fig. 45 1, into the elevated firing position, shown in Fig. 2, the bolt *g* is withdrawn from its locking position in line with the trunnion of the gun permitting the axle-tree, together with the gun carriage, to be moved in the 50 direction of the arrow, Fig. 1, and into the position shown in Fig. 2, the bolt *g* then taking into a hole *k* in the trail. This movement has the effect of raising the gun from lower to higher position. It can again be 55 lowered for the purpose of traveling to so distribute the masses of the gun barrel and other parts that they balance about the wheel axis. The trail therefore exerts no, or at least a very inconsiderable, pressure on the 60 shaft of the limber.

I claim as my invention:—

1. In combination, a gun, a carriage to which said gun is pivoted, a cranked axle mounted on the carriage, and means for securing said crank in line with the pivots of 65 said gun to counterbalance the masses about the wheel axle in traveling.

2. In combination with a gun and its carriage to which the gun is pivoted, a cranked 70 axle mounted on the gun carriage, and means for securing the crank of the axle in line with the gun pivots or at a lower point on the gun carriage when the gun is elevated.

3. In combination with a gun and its carriage to which the gun is pivoted, a cranked 75 axle mounted on the gun carriage, and means for securing the crank of the axle in line with the gun pivots or at a lower point on the gun carriage to the rear of the pivots 80 when the gun is elevated.

In testimony whereof, I have signed this specification in the presence of two subscribing witnesses.

KURT KLETTE. [L. S.]

Witnesses:

HELEN NUFER,
ALBERT NUFER.
